WRIST ATTACHMENT FOR INFANT'S EATING UTENSILS

Pearl Green, Brownsville, Pa.

Application July 3, 1950, Serial No. 10,934

Term of patent 14 years

(Cl. D54—12)

To all whom it may concern:

Be it known that I, Pearl Green, a citizen of the United States, residing at 407 Green Street, in the city of Brownsville, county of Fayette, State of Pennsylvania, have invented a new, original, and ornamental Design for a Wrist Attachment for Infant's Eating Utensils, of which the following is a specification, reference being made to the accompanying drawing, forming a part thereof.

Fig. 2 is a side view of Fig. 1.

The essential features of my design reside in the parts shown in full lines.

I claim:

The ornamental design for a wrist attachment for infant's eating utensils, substantially as shown and described.

PEARL GREEN.
